BELT LACING SETTING DEVICE

John C. Olsen, Chicago, Ill., assignor to Flexible
Steel Lacing Company, Chicago, Ill., a corpora-
tion of Illinois

Application August 24, 1936, Serial No. 97,622

14 Claims. (Cl. 1—49.4)

This invention relates to improvements in belt lacing setting device.

In applying metal belt lacings to the ends of belts, it has been the general practice heretofore to use either a hammer or a manually operated device. Experience has shown that while this was satisfactory in smaller establishments, the use of a hammer or other manually operated device is too slow and expensive in large establishments where a great number of belts must have fasteners applied on a regular production schedule. One object of this invention, therefore, is to provide a belt lacing setting device which may be used in and operated by a power press to the end that the lacings may be applied rapidly and with minimum effort.

Another object of the invention is to provide a belt lacing setting device of such construction that accurate and uniform attachment of the lacing to the belt, even though the belt be composed of easily flexible material, is always insured.

A specific object of the invention is to provide a power operated lacing setting device such that the holder for the lacing and usual gauge pin carried by the holder are freely movable in consonance with the edge of the belt as the teeth or prongs of the lacing are gradually forced into the belt material, thus preventing misplacement or distortion of the lacing during application and insuring true and proper positioning of the lacing with respect to the belt end when finally clinched thereto.

Still another object of the invention is to provide a setting device of the type previously indicated such that the cooperating parts are combined into two assembled units which may be readily mounted on and removed from the bolster plate and cross head of the punching or other similar power operated machine or press.

Other objects of the invention will more clearly appear from the description and claims herein-after following.

In the drawings forming a part of this specification, Figure 1 is an end elevational view of the improved device, showing the same associated with a power punch press and indicating the relative positions of the belt end, lacing, and other parts prior to the beginning of the clinching action. Figure 2 is a top plan view of the unit assembly which is mounted on the bolster plate of the press. And Figure 3 is a front elevational view of the device.

In said drawings, 10 indicates the bolster plate of a common type of power punch press, and 11

the reciprocating cross head movable toward and from the bolster plate, as will be understood. In carrying out the invention, a unit assembly is provided for attachment to the bolster plate 10, said unit assembly comprising a shoe 12, an anvil 13, a carrier indicated broadly by the reference A, and a belt guiding unit indicated broadly by the reference B. A second unit assembly, for attachment to the cross head 11, comprises a plate 14, a striking member 15 and a pressure pad or member 16.

Referring first to the assembly attachable to the bolster plate, the shoe 12 is in the form of a relatively heavy plate or block of rectangular form, suitably recessed to receive therein the anvil 13 in its upper face, the anvil being secured to the shoe 12 by suitable means such as the heavy machine screws 17. The anvil proper, of case hardened steel or other suitable material, is of elongated form and of sufficient length to permit application of the maximum length of belt lacing to be applied at any one operation. The striking face 18 of the anvil is slightly beveled or inclined with respect to the horizontal in a downward direction from the belt guide B, for the purpose hereinafter described and as clearly shown in Figure 1 and is more sharply beveled as indicated at 19 along opposite edges of the striking face 18.

Integrally formed with or otherwise rigidly united with the shoe 12 are two upstanding hinge lugs 20—20 in which is supported a hinge pin 21 having its axis extending parallel to the anvil 13. Carried by the hinge pin 21 are two arms 22—22 extending forwardly toward the anvil and which carry the holder proper for the lacing and gauge pin. Said holder proper comprises a comb 23 secured to the arms 22 by screws or bolts 24. The comb 23 is formed with alternated ribs or partitions 25 and recesses 26, the spacing of which corresponds to the spacing of the loops of the lacing which is to be applied, one form of which is indicated at 27. At the bottoms of the recesses 26, the comb is formed with inclined faces 28 as shown in Figure 1, and upper and lower plates 29 and 30 complete the comb. The ribs or partitions 25 are provided with alined perforations extending parallel to the anvil for reception of the usual gauge pin 31.

By inclining the striking face 18 of the anvil, the pressure may be applied to the teeth of the lacing while setting them flush in the belt without applying any pressure on the apices or loops proper of the lacing which might otherwise distort the loops. The overhanging plate 29, when

the lacing is in place, serves to hold the lacing down on the anvil when the teeth of the lacing are being forced through the belt material and thus prevents the lacing and belt end 32 from being relatively displaced from correct position.

5 The holder assembly A is normally yieldably held elevated in spaced relation to the anvil by suitable coil springs 33-33 interposed between the arms 22 and the shoe 12. Adjustable screws 10 34, mounted in brackets 35 secured to the shoe 12 by screws 36, are employed for the following purpose. After the lacing and gauge pin are in place in the comb, the lacing is allowed to rest on the anvil, engaging therewith along the points 15 indicated at 53. Sufficient clearance is allowed in the comb so that, by adjusting the screws 34, the lacing can be adjusted angularly around the gauge pin so as to set the lacing at the proper angle for the teeth thereon to assume the correct entering angle with respect to the belt end 32.

20 The belt guide unit B preferably comprises a block 37 secured to the shoe 12 by screws 38, said block 37 having secured thereto a base plate 39 to the side edges of which are adjustably secured edge guides 40 by means of the screws and slots 41 and 42, to thus adapt the belt guide to belts of varying width.

25 Referring next to the unit assembly secured to the cross head 11, said assembly comprises the heavy plate 14 heretofore referred to which is secured to the cross head 11 by heavy machine screws 43. Rigidly associated with the plate 14 is the striking member 15, heretofore referred to, the latter consisting of an elongated vertically 30 extending heavy plate, of suitable case hardened or heat treated steel or other material. The lower striking edge 44 thereof is so positioned as to engage the belt lacing initially along the prongs as indicated at 45, said striking edge 44 being cut back as indicated at 46 so as to insure 35 clearance with respect to the holder comb, as the striking member comes down, as will be understood. The pressure pad or member 16 consists of an elongated plate mounted on the striking 40 member 15 so as to have relative vertical movement with respect thereto, this mounting being effected through a plurality of screws 47 extending through vertically elongated slots 48 in the pressure member 16. The latter is normally 45 yieldably held with its lower edge 49 projecting slightly below the striking edge 44, by means of a series of coil springs 50 interposed between the pressure member 16 and a block 51 constituting a part of the assembly 14. Adjustable bumper 50 screws 52 may also be employed, the same being carried by the plate 14 and aligned with the arms 22 of the holder unit A, said bumper screws 52 being so adjusted that, at the final downward movement of the cross head and striking member 15, the holder unit A will be positively forced 55 downwardly should there be any tendency of the same to lag in following the lacing as the latter is clinched to the belt end.

60 As shown in Figure 1, the lacing is secured to the comb ready for application to the free end of the belt 32, the latter being held by the operator properly guided by the guide unit B and with the end edge of the belt up against the comb. When the clutch is thrown in for the cross head 11, the 65 latter descends and the striking edge 44 will initially engage the lacing along the line 45, previously referred to. As the downward movement of the cross head and striking member continues, the lower prongs of the lacing then begin to enter the material, as will be apparent. During the

clinching operation, it is obvious that the lacing holder and gauge pin will freely follow the penetrating action of the prongs, maintaining at all times a proper relation between the comb and gauge pin with reference to the end of the belt 5 and preventing angular or turning movement of the lacing with respect to the comb, thus insuring a true and proper application of the lacing to the belt end. In the case of some belts composed of relatively easily flexible material, there would be 10 a tendency for the belt material to bend or buckle in resisting the penetration of the prongs into the material. To counteract any such action, the pressure member 16 is employed, it being apparent that the bottom edge 49 thereof will engage the 15 belt just beyond the prongs and initially at a time somewhat after the striking edge 44 has engaged the lacing prongs and started the same into the material. As the down stroke continues, the pressure member 16 will gradually yield with 20 reference to the striking edge 44 and thus insure maintenance of the belt material in line with the comb and gauge pin, and also preventing displacement of the belt with reference to the lacing during the clinching operation and insuring proper 25 application of the lacing up to the final clinching action.

25 From the preceding description, it will be seen that the applying device, being made in two unit assemblies, can readily be mounted in and removed from a punch press or the like and provides an effective and efficient means for quickly applying belt lacings to belt ends.

30 In the drawings and description, reference has been had to "belt lacing" and one particular well 35 known form thereof illustrated. By the term "lacing" it is to be understood that the same is intended, both in the description and claims, to comprehend not only the type of belt lacing illustrated in the drawings wherein the loops are 40 united, but also all other forms of belt end attaching fasteners such as wire hooks and staples which are frequently mounted in gangs on cards for application to belt ends in a similar manner.

45 There has herein been shown and described what is now considered the preferred manner of carrying out the invention, but the same is by way of illustration and not by way of limitation since it will be apparent to those skilled in the art that various changes and modifications may be 50 made without departing from the spirit of the invention. All such changes and modifications are contemplated that come within the scope of the claims appended hereto.

55 What is claimed is:

1. In a belt lacing setting device, the combination with an anvil; of a holder for the belt lacing and gauge pin, said holder extending parallel to the anvil adjacent thereto; means pivotally supporting said holder to swing about an axis parallel to the anvil; and adjustable means for determining the initial free position of said holder relative to the anvil at the beginning of the setting operation.

2. In a belt lacing setting device, the combination with an anvil; of a holder for the belt lacing and gauge pin, said holder being disposed adjacent the anvil and movably mounted relative thereto; a striking member reciprocatingly mounted with reference to the anvil to engage the lacing; and a pressure member associated with the striking member adapted to engage the belt adjacent the lacing.

3. A belt lacing setting device in accordance with claim 2 wherein said pressure member is 75

- yieldably mounted relative to the striking member.
4. In a belt lacing setting device, the combination with an anvil; of a belt lacing and gauge pin holder yieldably normally supported in spaced relation to the anvil and movable toward the anvil during the clinching action of the lacing; means for adjustably determining the initial position of the holder relative to the anvil for the beginning of the setting operation; and a striking member engageable with the lacing while held in the holder, said striking member being movable toward and from the anvil.
5. In a belt lacing setting device, the combination with an anvil; of a belt lacing and gauge pin holder yieldably normally supported in spaced relation to the anvil; a striking member movable toward and from the anvil in line to engage the lacing while carried by the holder; and a yieldable pressure member carried by the striking member and adapted to engage the belt adjacent the lacing.
6. In a belt lacing setting device, the combination with an anvil; of a belt lacing and gauge pin holder movable toward the anvil during the clinching action of the lacing; adjusting and yieldable means normally supporting said holder in predetermined spaced relation to the anvil; and a striking member engageable with the lacing while held in the holder, said striking member being movable toward and from the anvil, said anvil, holder and yieldable means all being mounted on a common shoe to thereby provide a unitary assembly adaptable for attachment to the bolster plate or the like of a punch press.
7. In a belt lacing setting device, the combination with an anvil having the striking surface thereof slightly beveled; of a belt guide disposed adjacent the anvil; a holder for the belt lacing and gauge pin yieldingly pivotally supported adjacent the anvil opposite the belt guide; adjustable means governing the normal free position of said holder with reference to the anvil; and a striking member movable toward and from the anvil in a line intermediate the belt guide and holder and adapted to engage the lacing when held by the holder.
8. In a belt lacing setting device, the combination with an anvil having the striking surface thereof slightly beveled; of a belt guide disposed adjacent the anvil; a holder for the belt lacing and gauge pin yieldingly pivotally supported adjacent the anvil opposite the belt guide; adjustable means governing the normal free position of said holder with reference to the anvil; a striking member movable toward and from the anvil in a line intermediate the belt guide and holder and adapted to engage the lacing when held by the holder; and a belt-engaging pressure member yieldably movably mounted relative to and carried by said striking member.
9. In a belt lacing setting device for use in a power operated punch press or the like, the combination with an anvil, belt guide, and belt lacing and gauge pin holder unit assembly all mounted on a shoe adapted for attachment to the bolster plate of the press; of a striking member and associated pressure member assembly unit mounted on a common plate adapted for attachment to the cross head of the press.
10. In a belt lacing setting device, the combination with an anvil having a relatively elongated striking surface; of belt guiding means disposed adjacent the anvil along one side thereof; a lacing and gauge pin holder extending along the opposite side of the anvil and yieldably supported; a striking member also relatively elongated in alignment with the striking surface of the anvil, the striking member being movable toward and from the anvil; and a relatively elongated belt-engaging pressure member yieldably mounted with respect to the striking member and also movable toward and from the anvil.
11. In a belt lacing setting device, the combination with an anvil; of a belt guide disposed adjacent the anvil; a holder for the belt lacing, said holder being yieldingly and pivotally supported adjacent the anvil opposite the belt guide; a striking member reciprocatingly mounted toward and from the anvil in a line intermediate the belt guide and holder and adapted to engage the lacing when held by the holder; and a belt-engaging pressure member yieldably movably mounted relative to said striking member.
12. In a belt lacing setting device for use in a power operated punch press or the like, the combination of a unit assembly including an anvil, a belt lacing and gauge pin holder and a shoe to which the anvil and holder are secured, the unit assembly being adapted for attachment to the bolster plate of the press; of a second unit assembly including a striking member, an associated pressure member and a plate, said striking member and pressure member being secured to said plate and the unit being adapted for attachment to the cross-head of the press.
13. In a belt lacing setting device, the combination with an anvil; of a lacing striking member reciprocatingly mounted to move to and from the anvil; a holder for the belt lacing and gauge pin pivotally mounted adjacent the anvil, said holder including a comb formed to substantially prevent turning or shifting of the lacing within the comb during the setting operation; and adjustable means for regulating the normal free position of the comb relative to the anvil.
14. In a belt lacing setting device, the combination with an anvil having the striking face thereof inclined downwardly in one direction; of a holder for the belt lacing and a gauge pin, said holder being pivotally mounted on an axis disposed parallel to and spaced from the lower edge of the inclined striking face on that side remote from the upper edge of the inclined striking face; means yieldably retaining the holder in its initial position relative to the anvil for the beginning of the setting operation; and a striking member reciprocatingly mounted to move in a line to engage the belt lacing, when the latter is in the holder, at points directly opposite said inclined surface of the anvil.

JOHN C. OLSEN.
